(57) **CLAIM**

The ornamental design for an accessory storage box for vacuum cleaner, as shown and described.

DESCRIPTION

FIG. 1 is a front perspective view of an accessory storage box for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is a perspective view thereof in an alternate position. The even-dash broken lines illustrating portions of the accessory storage box form no part of the claimed design.

1 Claim, 9 Drawing Sheets
